UNITED STATES PATENT OFFICE.

CHARLES R. LAMBERT, OF DETROIT, MICHIGAN, ASSIGNOR TO CLAYTON & LAMBERT MANUFACTURING COMPANY, OF DETROIT, MICHIGAN, A CORPORATION OF MICHIGAN.

FIREPOT.

1,374,587.

Specification of Letters Patent. Patented Apr. 12, 1921.

Application filed May 4, 1918. Serial No. 232,445.

To all whom it may concern:

Be it known that I, CHARLES R. LAMBERT, a citizen of the United States of America, residing at Detroit, in the county of Wayne and State of Michigan, have invented certain new and useful Improvements in Firepots, of which the following is a specification, reference being had therein to the accompanying drawings.

10 This invention relates to fire pots or like devices and refers more particularly to a novel arrangement of supporting standard and guard plate supports for vessels of the general character above mentioned, although 15 it is of course understood that the invention is not necessarily limited to the particular construction with which it is described.

Among the objects of the invention are to provide a fire pot or similar construction 20 wherein the necessity of using cast parts is particularly avoided; to completely form the supporting standard or spider member from sheet metal bent into proper shape and preferably combined with a central hub 25 portion; to provide an improved and simplified construction of guard support which can be formed from sheet metal; and in general to provide an improved and simplified construction which can be more economically produced and which will be 30 lighter in weight than devices of this character now in use and still retain the necessary strength.

The invention also resides in other details 35 of construction and arrangements and combinations of parts as will more fully herein-after appear.

In the drawings:

Figure 1 is a side elevational view, partly 40 in section, of a fire pot embodying my invention;

Fig. 2 is a top plan view of the spider or supporting standard;

Fig. 3 is a side elevational view of the 45 parts shown in Fig. 2;

Fig. 4 is a vertical cross-section on line 4—4 of Fig. 3;

Fig. 5 is a top plan view of the guard plate support;

50 Fig. 6 is an end view of the parts shown in Fig. 5;

Fig. 7 is a top plan view of the fire pot shown in Fig. 1.

In portable fire pots or similar devices while light weight is desirable, it is necessary that the supporting standards or other parts have sufficient strength and rigidity to withstand the hard usage to which such devices are often subjected, particularly in carrying from one point to another. 55

Heretofore it has been customary to support the fire pot from the tank or other base by means of a cast metal member and the present invention particularly contemplates a new and improved arrangement of parts 60 whereby the use of a cast supporting standard is avoided and the advantages of a sheet metal member are secured.

In general the fire pot comprises the base or tank A and the sheet metal body B supported on the base by means of a standard C. This standard is formed as a spider member having a central hub D which fits over an upwardly extending fitting F secured to the tank A. A suitable set screw 65 D' is employed for locking the standard to the fitting.

In detail the spider arm comprises a sheet metal member bent to form a plurality of upwardly extending arms G, G' and G² 80 which at their upper ends are secured to the main body section B of the fire pot by means of suitable securing devices such as the rivets H. In the particular construction shown there are three of these arms and they are 85 bent to form a smooth inner face I which fits against the outer wall of the main body portion B, while at their rear side the arms are bent to form strengthening flanges J and J', giving a strong channel shaped reinforcement to the arms. At the lower end 90 of the arms the metal is bent inwardly and formed into cylindrically shaped portions K, K' and K², the metal then being continued downward in parallel relation, forming a vertical web L made up of the parallel portions L' and L². At their inner ends or central portion each of the cylindrical portions K and the vertical web portions L abut 95 against and are welded or otherwise secured to the hub portion D. A supporting spider formed as above described is not only light in weight but has its parts so shaped and proportioned as to produce an extremely strong and rigid member. Moreover, by 100 forming the supporting spider of sheet

105

metal the danger of breaking one of the arms in case the fire pot is dropped is avoided. The fitting F is also preferably formed by a stamping or other press operation so that the use of a casting between the fire pot and its tank or other supporting base is entirely done away with.

At its front the fire pot is usually provided with an opening N through which the tool is inserted into the fire pot and at the lower end of this opening there is placed a guard or hearth plate O. For pivotally supporting the outer end of this guard plate and to establish a rest for such tools as may be inserted through the opening N I have provided a novel arrangement of supporting member Q which is formed as follows: A piece of sheet metal is bent to provide a central cylindrical portion R which has forwardly bent arms R' and R''. These arms are formed with web portions S and flanges S' and S'' which form a channel and at their inner ends the arms are provided with segmental portions T and T' which are secured to the main body portion B by rivets, welding or other suitable means. At the junction of the cylindrical portion R and the arms R' and R'' the metal is preferably shaped to produce reinforcing rings V and V' which further strengthen the guard support and prevent the guard from moving laterally. By constructing the supporting member for the guard plate in substantially the manner above described, an extremely light weight member is produced without sacrificing the necessary strength and rigidity. The plate O will prevent solder, or the like, dripping upon the lower portion of the fire pot.

Another feature of my invention resides in the arrangement and provision of a sheet metal reinforcing ring and support at the upper end of the main body section B. Previously this reinforcement has been formed as a heavy casting member but in the present arrangement the ring W is formed from a flat piece of sheet metal bent into ring shape. At its upper end the reinforcing member W has a return-bent flange W' which may, if desired, contain a strengthening wire W''. It also has a depending flange W''' which fits closely against the inner surface of the upper edge of the main body section B. As this reinforcing ring W is also used as a support for the auxiliary melting pot Y, the ring is provided with inwardly projecting members Y' which are of the shape shown in Fig. 7. Also there is preferably formed upwardly extending projections Y'' which serve to retain a cover when the auxiliary melting pot is not employed.

In addition to the uses above mentioned part of the ring W is also utilized as a stop 65 for preventing the bail Z from moving be-

yond center. As shown in Fig. 7 the eyelets Z' for the bail are located forwardly of the center line of the fire pot. When, however, the soldering irons are placed in the fire pot and rest on the guard plate O they will tend to swing the forward end of the fire pot down. As the flange W' of the ring W has cut-away portions near the projections Y', I utilize the abutment shoulders Z'' and Z''' as stops for preventing the bail from swinging beyond the center of the fire pot.

From the above description it will be noticed that practically the entire fire pot is formed from sheet metal and that the shape and construction of the fittings are such as to give sufficient rigidity to the structure. I do not, however, desire to limit the invention to the particular details shown and described as various changes would suggest themselves to those skilled in the art.

What I claim as my invention is:—

1. In a fire pot, the combination with a main body portion and a tank or other supporting member, of a sheet metal standard mounted on said tank and having integral upwardly extending arms secured to said body portion.

2. In a fire pot, the combination with a main body portion and a tank or other supporting member, of a sheet metal standard mounted on said tank and having integral upwardly extending arms secured to said body portion, said body portion being provided with a shield and a sheet metal support for said shield.

3. In a fire pot, the combination with a main body portion and a tank or other supporting member, of a sheet metal standard mounted on said tank and having integral upwardly extending arms secured to said body portion, said body portion being provided with a shield and a sheet metal support for said shield, said support being bent to form a central cylindrical portion connected to the channel shaped arms.

4. The combination with a fire pot having a main body portion provided with a shield, of a support for said shield comprising a sheet metal member bent to form a central cylindrical portion, and channel shaped arms terminating in segmental portions secured to said main body portion.

5. The combination with a fire pot having a main body portion provided with a shield, of a support for said shield comprising a sheet metal member bent to form a central cylindrical portion, channel shaped arms terminating in segmental portions secured to said main body portion, and reinforcing rings formed at the junctions of said arms with said cylindrical portion.

6. The combination with a fire pot having a main body portion provided with a guard, of a pivotal support for said guard comprising a sheet metal member forming a pivot

for said guard and having arms secured to said main body portion.

7. In a fire pot, the combination with a main body portion formed of sheet metal, 5 of a reinforcing ring for the upper end of said body portion, said ring being formed of sheet metal and having integral inwardly projecting supporting flanges.

8. In a fire pot, the combination with a 10 main body portion formed of sheet metal, of a reinforcing ring for the upper end of said body portion, said ring being formed of sheet metal and having integral inwardly projecting supporting flanges and upstanding 15 projections for retaining a cover.

9. In a fire pot, the combination with a main body portion and a bail for said main body portion connected thereto at one side of the center, of a reinforcing ring for the 20 upper end of the main body portion, said ring having a cut away portion receiving the bail and maintaining the latter substantially upright.

10. In a fire pot, the combination with a 25 main body portion, and a tank or other supporting member of a sheet metal standard, mounted on said tank and comprising a boss engaging the tank and integral divergent arms, supporting said body at an elevation above the tank.

11. In a fire pot, the combination with a main body portion formed of sheet metal, of a reinforcing ring having a rolled edge pro-

jecting above the edge of said body portion and having a radial inward projection for 35 supporting a vessel on the fire pot.

12. In a fire pot, the combination with a main body formed of sheet metal, of a reinforcing ring, engaging the upper edge of said body portion and folded at intervals to 40 form radial inward projections forming supports for the vessel to be heated by the fire pot.

13. The combination with a fire pot having a main body portion having an opening 45 for the insertion of tools in said portion, of a support for such tools, comprising a sheet metal member bent to form a central cylindrical portion and further forming channel shaped arms, secured to said main 50 body portion, adjacent to said opening.

14. The combination with a fire pot having a main body portion formed with an opening for the insertion of tools in said body portion, of a support for such tools 55 comprising a sheet metal member, forming a central cylindrical portion, and channel shaped arms at each side of said cylindrical portion, terminating in segmental portion secured to said main body portion, and 60 provided with reinforcing rings formed at the juncture of said arms with said cylindrical portion.

In testimony whereof I affix my signature.

CHARLES R. LAMBERT.
